UNITED STATES PATENT OFFICE.

FRANK B. RIVERS, OF BOYNE CITY, MICHIGAN.

AUTOMATICALLY-FEEDING OIL-CUP.

1,195,856.

Specification of Letters Patent. Patented Aug. 22, 1916.

Application filed June 23, 1914. Serial No. 846,804.

To all whom it may concern:

Be it known that I, FRANK BYRON RIVERS, a citizen of the United States, residing at Boyne City, in the county of Charlevoix and 5 State of Michigan, have invented certain new and useful Improvements in Automatically-Feeding Oil-Cups; and I do hereby declare the following to be a full, clear, and exact description of the invention, such as 10 will enable others skilled in the art to which it appertains to make and use the same.

This invention comprehends certain new and useful improvements in oil cups and has for its primary object to provide a device of this character which will be of such 15 construction and operation that the oil will be fed from the reservoir thereof to the feeding stem leading to the member or members to be oiled or lubricated by a capillary 20 attraction.

Another object of the invention is to provide a device of this character which will be of extremely simple and cheap construction as well as highly efficient and durable 25 in use.

The invention has for a further object to provide a device of this character which will be constructed in such manner that the amount of oil to be fed by the same to the 30 portion of the machinery to be oiled or lubricated, may be readily regulated, as desired.

With these and other objects in view as will become more apparent as the description 35 proceeds, the invention consists in certain novel features of construction, combination and arrangement of parts as will be hereinafter more fully described and claimed.

For a complete understanding of my invention reference is to be had to the following description and accompanying drawings, in which—

Figure 1 is a longitudinal vertical section 45 through the complete device, and Fig. 2 is a detail elevation of the feeding means and the support for the same removed.

Referring in detail to the drawings by numerals, 1 designates an oil cup proper or 50 reservoir, the upper open end of which is closed by a suitable cap 2 having its edge turned down to form the flange 3 engaged around the upper portion of said reservoir 1, when the cap 2 is in position.

Depending from the bottom of the reservoir 55 1 around the outlet opening 4 thereof

is the exteriorly threaded feeding stem 5 which may be readily secured to any portion of a machine or the like to lubricate or oil parts thereof.

60

Projecting upwardly into the cup 1 is a tubular wick receiving member 6 that is of considerably less diameter than the cup 1 and spaced at its free end considerably from the open end of the cup 1. The upper open 65 end is preferably disposed adjacent to the center of the cup.

I have provided a wick designated 7 as an entirety that preferably consists of a number of strands of wool yarn or the like 70 which strands are secured to one another centrally of their ends by a wick supporting member 8. The lower end of the wick supporting member 8 is bent about so as to clamp the strands, as at 9. The other end 75 of the wick supporting member is turned inwardly to form a hook 10 that is designed to engage upon the upper edge of the wick receiving member 6. The holding member 8 consists of a relatively spaced body portion with the hook 10 and angularly extending 80 clamping end 9.

In operation the oil or lubricant is forced through the cup until it reaches a level below the upper working end of the tubular 85 member 6. The wick holding member 8, after the wick has been secured thereto, is inserted into the tubular member 6 and the hook end 10 thereof engaged with the upper 90 edge of the member 6 so that the wick is supported. The central portion of the wick is positioned within the tubular member 6, shown in section, while the ends thereof 95 overhang the tubular member and dispose themselves into the lubricant contained in the cup. The wick draws the lubricant upwardly and into the member 6. The lubricant drops from the lower end of the wick that is disposed within the member 6 and to the parts to be lubricated. The stem 5 100 communicates with the tubular member 6 and both stem and tubular member are formed integral with the cup preferably, to provide rigidity and enable cheap construction of the device as the cup and parts 105 thereon may be cast when formed of such construction. The stem 5 is threaded and turned into the bearing or parts of the machine to be oiled.

It will be readily seen that a machine may 110 be properly lubricated and in such manner that undue waste of oil is prevented. By

removing the cap 2 ready access to the wick 6 may be had, and it is only necessary to grasp the hook end 10 of the holding member 8 to remove the wick for the purpose of 5 clamping or renewing the same.

In practice I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion 10 and arrangement of parts may be resorted to, when required, without sacrificing any of the advantages of my invention as set forth.

What is claimed is:—

20 A lubricating cup comprising a cylindrical body having one end open, its opposite end being rounded and provided with a cen-

tral opening, a feeding stem extending downwardly from said opening, its lower end being exteriorly screw-threaded for attaching the cup in place, a wick tube extending upwardly from the opening, its upper end terminating adjacent the center of the cylindrical body, a wick supporting member having an eye at one end and a hook at its 25 opposite end, said hook of the supporting member secured over the upper end of the wick tube, the eye of the same depending into said tube, a wick supported in the eye of said supporting member, the ends of said 30 wick terminating in the bottom of the cup, and a cover fitted over the upper open end of said cylindrical body.

In testimony whereof I affix my signature in presence of two witnesses.

FRANK B. RIVERS.
